UNITED STATES PATENT OFFICE.

HENRY C. FRAHM, OF HALCYON, CALIFORNIA.

PUMP.

1,331,846.

Specification of Letters Patent.

Patented Feb. 24, 1920.

Application filed May 22, 1918. Serial No. 235,983.

To all whom it may concern:

Be it known that I, HENRY C. FRAHM, a citizen of the United States, residing at Halcyon, in the county of San Luis Obispo and State of California, have invented certain new and useful Improvements in Pumps, of which the following is a specification.

This invention relates to pumps, and more particularly to a pump of the double acting type.

One of the main objects of the invention is to provide a pump of the character described of simple construction and operation, and capable of pumping a relatively great quantity of water in a given time.

A further object is to provide a pump composed of a minimum of parts in which the piston, when moved in either direction, will force water into the outlet and will simultaneously draw water into the inlet, thus insuring smoothness of operation and avoiding unnecessary vibration.

A still further object is to provide a pump which may be readily assembled or disassembled for cleaning, repairs, and other purposes.

Further objects will appear from the detailed description.

30 In the drawings:—

Figure 1 is a top plan view of a pump constructed in accordance with my invention partly broken away to show the interior construction.

35 Fig. 2 is a sectional view taken substantially on line 2—2 of Fig. 1.

Fig. 3 is a central longitudinal section.

Fig. 4 is an end view taken from the discharge or outlet end, partly in section.

40 The pump casing designated generally by A is provided with a central cylindrical body portion 1 which is enlarged at one end to provide an inlet valve casing 2 projecting downwardly beneath the body 1, the outer end of this casing being normally closed by a cap plate 3, detachably secured thereto by securing bolts 4 passed through the cap and threaded into the body of the casing. An upwardly flaring inlet connection 5 is secured to the lower end of the casing 2 by bolts 6 which are inserted through the flange 7 at the upper edge of the connection and threaded into the lower portion of the valve casing. A valve plate 8 is secured between the connection 5 and the casing 2 by means of these bolts, this plate

being provided with spaced openings, and threaded to receive supporting spiders 9 secured therein. Each of the spiders is provided with a central hub 10 in which is secured the lower end portion of a valve pin 11 on the upper end of which is threaded a flange cap 12 which slidably receives the neck 13 of a disk valve 14 which is normally forced downwardly by a coil spring 15, 60 mounted about the neck of the valve and confined between the valve body and cap 12. These valves 14 act to normally close the inlet openings between the inlet valve casing 2 and the inlet connection 5. The body 70 1 is further provided, at its forward end, with an outlet casing 17 formed integral therewith, this casing having a lower portion 18 and an upper substantially rectangular portion 19, these two portions of the casing being separated by a central horizontal web 20 which serves to divide the casing into upper and lower compartments. This web is provided adjacent each side of the casing 17, with an outlet opening and is threaded 75 to receive a spider 21 similar to the spiders 9, which carries a pin 22 slidably receiving the neck 23 of a disk outlet valve 24 normally held in seated position by an expansion coil spring 25 confined between the body 80 of the valve and the flange cap 26 secured on the upper end of pin 22. These valves serve to control communication between the water receiving spaces 27 and the exhaust chamber 28.

90 A pump cylinder 30 is mounted in the casing A concentric with body 1 thereof. This cylinder corresponds in length, approximately, to the interior length of the casing and fits snugly between the upper 95 arcuate web member 31 formed integral with the top portion of the body 1 and inlet casing 2 and the web 20 of outlet or exhaust casing 17, and the arcuate member 32 formed integral with the lower portions of the body 100 1 and the lower portion 18 of the exhaust casing 17. As will be noted more clearly from Fig. 3, the forward end of cylinder 30 fits tightly against the front closure plate 33 of the exhaust casing 17, a suitable packing ring or gasket 34 being provided in the plate 33 for the reception of the forward end portion of the cylinder so as to insure a fluid tight closure therefor. The lower portion of the rearward end portion of the 110 cylinder 30 fits tightly in the arcuate head 37 of a partition member 38 which is se-

cured to the valve plate 8 mid-way between the inlet valve 24 and serves to divide, in conjunction with cylinder 30, the interior of the inlet casing 2 into two separate inlet compartments 39 and 40. As will be evident, the cylinder 30 also serves to provide two water passages 41 and 42 which extend along each side of the cylinder and communicate, at their forward ends, with the water compartments 27 of the lower portion 18 of the casing 17. A closure plug 43 is mounted in the rearward end of cylinder 30. This plug is of semi-circular outline, and has its greatest axis directed vertically thus dividing the end of the cylinder into two equal parts, and forming a semi-circular inlet opening 44 which establishes direct communication between the rearward end of the cylinder and the inlet compartment 39. As will be clear from Fig. 3, this plug is provided with a shoulder 43^a which acts as a spacing member to hold the rearward end of the cylinder 30 in spaced relation to the inner face of closure plate 3 for casing 2, thus insuring free flow of water in either direction through opening 44. Cylinder 30 is further provided, adjacent its forward end, with an opening 45 which communicates directly with the outlet water compartment 27 with which the water passage 41 communicates. Suitable elbows 46 communicate with the exhaust compartment 38 of the exhaust valve casing 17 so as to permit the water to be conveyed to the usual airdome or head with which the discharge pipe communicates, or if preferred, the water may be discharged directly from the casing 17. To permit ready access to the interior of the exhaust valve chamber, a cap plate 47 is secured on the upper end of the casing 17 by cap screws 48 so as to be detachable therefrom.

A piston 49 fits snugly in the cylinder 30 and is adapted to be reciprocated therein by means of the piston rod 50 which may be connected to any suitable operating mechanism. When the piston is drawn outwardly or toward the front of the pump casing A, the inlet valve 14 which is positioned within the inlet compartment 39 will be raised so as to permit water to be drawn into this compartment and into the cylinder in front of the piston 49. When the piston is moved rearwardly in the cylinder, the valve in inlet compartment 39 will be closed and the water within the cylinder 30 in back of the piston will be forced out of the cylinder through the opening 44 into the compartment 39, this water being then forced through the passage 42 into the outlet compartment 27 with which this passage communicates. This results in unseating the exhaust valve 24 so as to permit the water to flow into the exhaust chamber 28, and through the outlet 51 thereof into the elbow 46. Also, during this rear-

ward movement of the piston 49, a vacuum will be formed in the cylinder 30 in front of the piston thus causing the other inlet valve 14 to be raised or unseated so as to admit water into the inlet compartment 40 and into the cylinder 30 through the water passage 41 and the outlet compartment 27 with which this passage communicates. When the piston is again moved toward the front of the casing, this water will be forced through the opening 45 into the compartment 27, so as to unseat the other exhaust valve 24, the water then flowing into exhaust chamber 28 and through the openings 51 thereof and elbows 46. By this construction, when the piston of the pump is moved in either direction, water will be forced into the exhaust chamber 28, and an equal quantity of water will be simultaneously drawn into the pump casing so as to be forced into the exhaust chamber when the piston is moved in the opposite direction. This insures a pump which is capable of pumping a relatively great quantity of water or other fluid within a comparatively short time, and also serves to eliminate unnecessary jar or vibration, as the piston is at all times working against a cushion formed by the water being expelled from the pump.

By removing the end plates of the casing, the piston may be readily detached from the piston rod 50, by means of any suitable instrument, the closure plug 43 being first removed from the end of the cylinder. Also, the cylinder may be readily removed from the casing, thus permitting the pump to be quickly and easily disassembled for cleaning, repair and similar purpose.

The foregoing description and the drawings, have reference to what may be considered the preferred or approved, form of my invention. It is to be understood that I may make such changes in construction and arrangement and combination of parts, materials, dimensions, etc., as may prove expedient and fall within the scope of the appended claims.

Having thus described my invention what I claim as new and desire to secure by Letters Patent is:—

1. In a device of the character described, the combination of a pump casing consisting of a central cylindrical body portion provided with a cylinder extending therethrough and projecting therebeyond, a divided outlet casing formed at one end of said body and extending thereabove, thus forming a plurality of compartments, valve means for each compartment, a divided intake valve casing upon the opposite end of said body and depending therebelow, thus forming a pair of compartments in said intake casing, valve means in said intake casing, means for forming communication between said cylinder and body portion, and

piston reciprocal within said cylinder casing, all for the purposes set forth.

2. In a device of the class described, the combination of a cylindrical body portion having an intake valve casing at one end thereof and an outlet casing at the opposite end thereof, said intake valve casing having a horizontal valve plate, valve members carried by said plate, a partition member carried by the central portion of said valve plate and having an arcuate head on its upper portion, a pump cylinder extending through said cylindrical body and extending into each of said casings, said pump cylinder being smaller than said cylindrical body to form passage ways upon the exterior of the cylinder, said cylinder resting upon said arcuate head, thereby forming a pair of compartments in said intake casing,

a horizontal web carried within said outlet casing and having an arcuate web thereon, said pump cylinder engaging said last mentioned arcuate web, thus forming a plurality of compartments in said outlet casing, valve means carried by said horizontal web, where- 25 by a valve means will communicate with each of said last mentioned compartments, intake means connected to the intake casing, valve means connected to the outlet casing, and a piston reciprocally mounted within 30 said pump cylinder.

In testimony whereof I affix my signature in presence of two witnesses.

HENRY C. FRAHM.
